C. L. GOODRUM.

TELEPHONE EXCHANGE SYSTEM,
APPLICATION FILED SEPT. 17, 1917.

1,278,331.

Patented Sept. 10, 1918.

UNITED STATES PATENT OFFICE.

CHARLES LANE GOODRUM, OF NEW YORK, N. Y., ASSIGNOR TO WESTERN ELECTRIC COMPANY, INCORPORATED, OF NEW YORK, N. Y., A CORPORATION OF NEW YORK.

TELEPHONE-EXCHANGE SYSTEM.

1,278,331.

Specification of Letters Patent. Patented Sept. 10, 1918.

Application filed September 17, 1917. Serial No. 191,765.

To all whom it may concern:

Be it known that I, CHARLES L. GOODRUM, a citizen of the United States, residing at New York, in the county of New York and 5 State of New York, have invented certain new and useful Improvements in Telephone-Exchange Systems, of which the following is a full, clear, concise, and exact description.

- 10 This invention relates to telephone exchange systems, and more particularly to circuit arrangements for selector switches employed in automatic or semi-automatic telephone exchanges.
- 15 It is the object of this invention to provide an arrangement for a final selector or connector switch, especially adaptable for use in private branch exchange telephone systems, by the use of which, it is possible 20 for a called party to hold a connection, call a third party and after disconnecting the third party, return to the original connection.

According to this invention the calling 25 subscriber in a full automatic or an operator in a semi-automatic sends out impulses to set up a connection through selector and connector switches with the desired party. If the called party, for any reason wishes 30 to converse with a third party, the impulse sending device at the called station is operated to send out a predetermined number of impulses. This causes the talking conductors leading to the called station to be 35 disconnected and the called station may in the usual manner call any desired station in the system. After conversation is completed the receiver is replaced momentarily upon the switchhook, which action disconnects 40 the third party and connects again the calling party. Upon termination of conversation the switching apparatus is returned to normal position by the calling subscriber placing his receiver upon the hook. More specifically the connector 45 switch is provided with a magnet, which performs the double function of moving the brushes of the side switch associated therewith and of a cutoff relay for disconnecting 50 the called from the calling line during the time of calling and of conversation with the third party.

The drawing represents diagrammatically an automatic telephone exchange system,

and more in detail the circuit of a final 55 selector or connector switch, only so much being shown of the apparatus and circuits as is necessary for a clear understanding of the invention.

The subscriber at substation A desiring 60 to establish a connection with a substation B, removes his receiver from the switchhook and operates a calling device 3 for extending his line by means of switching mechanism comprising a selector switch 4 65 to an incoming line or trunk leading to a selector switch 5. A circuit is closed from grounded battery through the left hand winding of a line relay 6, the calling incoming line circuit and the right hand winding 70 of relay 6, to ground. Relay 6 by attracting its armature closes an energizing circuit for a slow-acting relay 7.

The subscriber at substation A proceeds 75 now to send out the tens and units impulses for controlling the setting of the final selector or connector. By operating the impulse sending device 3, the subscriber produces short interruptions in the incoming line circuit for intermittently deenergizing 80 and energizing relay 6. In response to the first deenergization of relay 6 a circuit is closed from grounded battery through the winding of primary magnet 8, a wiper 9 of 85 a side switch associated with connector 5, conductor 10, the front contact and armature of the relay 7, and the back contact and armature of relay 6 to ground. A further circuit is closed from ground through the armature and back contact of relay 6, 90 conductor 10, conductor 11, wiper 12 (first position), and the winding of slow acting relay 13 to grounded battery.

In response to each deenergization of relay 6, magnet 8 receives an impulse and 95 causes the stepping of the connector brushes to select a group of outgoing lines in which the line leading to the called substation B is located. Relays 7 and 13 being slow to release, remain energized during the vibration 100 of the armature of relay 6. Upon the energization of relay 13, a circuit is closed from grounded battery through the lower winding of slow-acting escapement magnet 14, side switch wiper 15 (first position), the front 105 contact and right hand armature of relay 13 and the back contact and armature of relay 16 to ground. Escapement magnet 14 be-

comes energized and is maintained actuated during the sending out of a series of impulses.

- After the tens impulses are sent out, the 5 incoming line circuit is closed and relay 6 remains energized for a sufficient period to permit the deenergization of slow acting relay 13, whereupon the circuit of magnet 14 is opened. This magnet becomes deenergized and allows the side switch wipers to escape into position 2. In this position of the side switch, primary magnet 8 is disconnected and the secondary magnet 17 is connected in the circuit. 10
- 15 The subscriber at substation A now proceeds to send out the units impulses. Relay 13 and magnet 14 become energized in the same manner as above described, but the impulses repeated by relay 6 are transmitted 20 to a secondary magnet 17 instead of to the primary magnet 8.

Under the control of magnet 17 the brushes of connector 5 are stepped onto the line leading to the called substation B. After the 25 sending out of the units impulses, relay 6 retains its armature attracted and opens the circuit of relay 13. Relay 13 releases and opens the circuit of magnet 14, which is made slow to release, so that the desired line 30 is tested before magnet 14 releases. As soon as the test brush 21 reaches terminal 20 individual to the called station, and if this station is not engaged in conversation as a calling or called subscriber, a circuit is established from grounded battery through winding of relay 40, terminal 20, brush 21, side switch wiper 22 (second position), conductor 23, left hand armature and back contact of relay 13, right hand winding of relay 35 40, to grounded battery. This circuit is closed before escapement magnet 14 is released. The called line being idle, relay 24 does not become energized due to the circuit just traced. The circuit of slow release magnet 14 is opened by the deenergization of relay 13. Magnet 14 becomes deenergized and moves the side switch brushes into position 3.

In position 3 of the side switch, a circuit is closed from grounded battery, ringing 50 current generator 25, winding of slow acting relay 16, side switch wiper 26, back contact and lower armature of escapement magnet 14, the called substation loop, upper outer armature and back contact of escapement 55 magnet 14, side switch wiper 27, to ground, for signaling the called station. A further circuit is closed from grounded battery, winding of relay 13, side switch wiper 12, front contact and armature of relay 6, to 60 ground. As soon as the called subscriber removes his receiver from the switchhook, relay 16 becomes energized and closes the circuit of escapement magnet 14, whereupon the side switch wipers are moved into position 65 4 due to the following circuit being

closed. Grounded battery, lower winding of magnet 14, side switch wiper 15 (third position), front contact and armature of relay 16 to ground. It should be noted that the teeth on the escapement magnet are so arranged that in positions 1 and 2 of the side switch the wipers are moved forward on deenergization of the escapement magnet while in position 3 the wipers are moved forward on energization. 75

In positions 3 and 4 of the side switch a ground is connected through the side switch wiper 22 to terminal 20 and the multiples thereof for making the selected lines inaccessible to other incoming calls. 80

Upon the termination of the conversation, the calling subscriber replaces his receiver upon the hook, opening thereby the circuit of relay 6. Relay 7 becomes deenergized and a circuit for the release magnet 30 is closed from grounded battery, through the winding of release magnet 30, off normal contact 31, back contact and armature of relay 7 and back contact and armature of relay 6, to ground. This circuit remains 90 closed as long as contact 31 is closed, *i. e.*, until connector 5 returns to its normal position, magnet 30 causing the restoration of the side switch and connector 5 to normal. 95

If the called line is busy, *i. e.*, if ground is connected to terminal 20, the above traced circuit of relay 24 results in the energization of this relay. Relay 24 closes a locking circuit for itself from grounded battery through the left hand winding, front contact and inner left hand armature thereof and through the front contact and armature of relay 6, to ground. A circuit is also closed from ground through the secondary winding of inductance coil 48, right-hand armature and front contact of relay 24, conductor 52, the calling sub-station loop and the left hand winding of relay 6 to grounded battery. A characteristic signal is sent to the calling substation from an alternating 100 source 51 for indicating the busy condition 105 of the desired line. 110

The calling subscriber restores his receiver to the switchhook opening thereby the incoming line circuit. Relays 6 and 7 become 115 deenergized and a circuit for release magnet 30 is established from grounded battery, through winding of release magnet 30, off normal contact 31, back contact and armature of relay 7 and back contact and armature of relay 6 to ground. Magnet 30 becomes energized and causes the restoration 120 of the side switch wipers and the connector 5.

Selector 4 and the other apparatus employed in the building up of the connection are restored to normal in any well known manner. 125

Assuming that the subscriber at substation B desires to converse with the subscriber at 130

substation C, it is necessary that his cut-off relay 40 be deenergized in order to reconnect the line relay 41 to his line. This is accomplished by the subscriber at substation B 5 operating his sending device 42 to transmit any desired number of impulses. When the relay 28 deenergizes in response to the impulses from the sending device 42 the slow releasing relay 13 becomes energized over a 10 circuit extending from grounded battery, winding of relay 13 side switch wiper 12 (fourth position), front contact and armature of slow release relay 18, back contact and armature of relay 28, back contact, upper 15 inner armature of escapement magnet 14 and back contact thereof to ground. The relay 18 attracts its armature and closes a circuit for escapement magnet 14, through ground, armature and back contact of relay 20 16, armature and front contact of relay 13, side switch wiper 15 (fourth position) lower winding of escapement magnet 14, to grounded battery. Escapement magnet 14 is energized and its armatures are attracted, 25 thus cutting off the called from the calling line.

The cutoff relay has its energizing circuit temporarily interrupted at the upper inner armature and back contact of escapement 30 magnet 14 and retracts its armature to connect the line relay 41 to B's line. The line relay 41 in operating causes the line switch, which is diagrammatically indicated at 44, to connect B's line to an idle selecting switch 35 diagrammatically indicated at 45. The line switch 44 in operating causes the operation of the cut-off relay 40 due to ground on lead 46. A holding circuit for slow release magnet 14 is also established through grounded 40 battery upper winding thereof, front contact and upper inner armature thereof, side switch wiper 22, (fourth position) brush 21, terminal 20 and conductor 46 to ground.

When the subscriber at sub-station B desires to disestablish his connection with the subscriber at station C, he momentarily replaces his receiver on its switchhook. This causes the line switch and the other switches employed in establishing the connection to 45 substation C to be restored in the well known manner. The release of the line switch causes the momentary deenergization of the cut-off relay 40 and also causes the deenergization of escapement magnet 14. The 50 escapement magnet 14 upon deenergization again completes the conversational circuit between the subscribers A and B and the cutoff relay 40 and relay 28 are again energized.

55 At the close of conversation the restoration of the connector switch, which is under control of the calling subscriber, is brought about by the subscriber at substation A replacing his receiver on its switchhook. This 60 interrupts the energizing circuit of the slow

releasing relay 7, causing it to retract its armature. An energizing circuit is thereupon completed for the release magnet 30. This circuit extends from grounded battery, winding of release magnet 30, off normal 70 contact 31, back contact and armature of relay 7, and back contact and armature of relay 6 to ground.

What is claimed is:

1. In a telephone exchange system, a plurality of stations, means including an automatic switch for interconnecting a calling and a called station, and a combined cutoff relay and side-switch magnet for simultaneously disconnecting said called station from 75 said calling station and for placing said called station in condition to establish a connection to a third station.

2. In a telephone exchange system, a plurality of lines, means including an automatic switch for interconnecting a calling line with a called line, a combined cutoff relay and side-switch magnet arranged to disconnect said called line from said calling line and to place said called line in condition to establish a connection to a third line, and means controlled by the called 85 party for operating said combined relay and magnet.

3. In a telephone exchange system, a plurality of lines, means for interconnecting a calling line with a called line, means for transmitting impulses, and a combined cutoff relay and side-switch magnet arranged to be controlled by said impulse transmitting 95 means to simultaneously disconnect said calling line from said called line and to place said called line in condition to establish a connection to a third line.

4. In a telephone exchange system, a plurality of lines, means for interconnecting a calling line with a called line, means associated with the called line for transmitting impulses, and a combined cutoff relay and side-switch magnet arranged to be controlled 105 by said impulse transmitting means to simultaneously disconnect said calling line from said called line and to place said called line in condition to establish a connection to a third line.

5. In a telephone exchange system, a calling line, a called line, a third line, impulse transmitting means, means including an automatic switch for connecting said calling line with said called line, means including 110 a combined cutoff relay and side-switch magnet controlled by said impulse transmitting means for disconnecting said called line from said calling line and for placing said called line in condition to establish a connection to said third line, means for establishing said connections to said third line, means to release said last mentioned connection, and means controlled by said disconnection for actuating said combined cutoff 115 120 125 130 relay.

relay and side-switch magnet to reëstablish communication between said calling and called lines.

6. In a telephone exchange system, a calling line, a called line, a third line, a non-numerical switch associated with said called line and normally arranged to be operated by the removal of the receiver of said called line, means including an automatic switch for connecting said calling line to said called line, means controlled by the establishment of said connection for rendering said non-numerical switch ineffective, means under

10 the control of the calling line for releasing

said connection, means associated with the 15 called line for transmitting impulses, and a combined cutoff relay and side-switch magnet arranged to be controlled by said impulse transmitting device for disconnecting said called line from said calling line and 20 for rendering the non-numerical switch associated with the called line operative to enable said called line to establish a connection to said third line.

In witness whereof I hereunto subscribe 25 my name this 13th day of September, A. D. 1917.

CHARLES LANE GOODRUM.
